The ornamental design for a foldable bag filler, as shown and described.

DESCRIPTION

FIG. 1 is a perspective view of a foldable bag filler showing my new design, in an expanded configuration;

FIG. 2 is a front elevational view thereof, a rear elevational view being a mirror image thereof;

FIG. 3 is a right side elevational view thereof, a left side elevational view being a mirror image thereof;

FIG. 4 is a top plan view thereof;

FIG. 5 is a bottom plan view thereof;

FIG. 6 is a perspective view of the foldable bag filler, in a collapsed configuration;

FIG. 7 is a front perspective view thereof, a rear elevational view being a mirror image thereof;

FIG. 8 is a right side elevational view thereof, a left side elevational view being a mirror image thereof;

FIG. 9 is a top plan view thereof; and,

FIG. 10 is a bottom plan view thereof.
